UNITED STATES PATENT OFFICE.

FRANCIS J. BAYER, OF NEW YORK, N. Y., AND ALBERT J. ROSENTRETER, OF BOONTON, NEW JERSEY, ASSIGNEES, BY MESNE ASSIGNMENTS, TO BAYER-GARDNER-HIMES COMPANY, A CORPORATION OF NEW JERSEY.

DOOR CLOSER AND CHECK.

1,113,184.

Specification of Letters Patent.

Patented Oct. 13, 1914.

Application filed July 1, 1913. Serial No. 776,761.

To all whom it may concern:

Be it known that we, FRANCIS J. BAYER, a citizen of the United States, residing in the city of New York, borough of Brooklyn, in the county of Kings and State of New York, and ALBERT J. ROSENTRETER, a citizen of the United States, residing at Boonton, in the county of Morris and State of New Jersey, have invented a certain new and useful Improvement in Door Closers and Checks, of which the following is a specification.

The invention relates to spring actuated door-closers and checks in which the closing movement is controlled by a liquid.

The object of the invention is to provide mechanism of simple and economical construction, adapted to serve with either right or left-hand doors with but little change and without substitution of parts, and capable of easy application under all conditions.

Other important objects are, to provide adjustable means for holding the door in the open or partially open position when desired; means for easily and quickly replacing the actuating spring; for reliably supporting the holding pawl, and for lessening the danger of leakage of checking liquid.

The invention consists in certain novel features and details of construction and arrangement by which the above objects are attained, to be hereinafter described and pointed out in the claims.

The accompanying drawings form a part of this specification and show the invention as it has been carried out in practice.

Figure 1 is a plan view of the device applied on a door. The dotted lines show the positions assumed by the parts when the door is partly open. Fig. 2 is a corresponding front elevation. Fig. 3 is a side elevation. Fig. 4 is a vertical section through the checking mechanism, with certain portions omitted. Fig. 5 is a side elevation of the checking mechanism and its supporting plate. Fig. 6 is a corresponding plan or top view. Fig. 7 is a similar view from below. Fig. 8 is a vertical section partly in elevation, showing the closing spring and its enclosing tube. Fig. 9 is a plan view of a latch forming part of the hold-back means for holding the door open. Fig. 10 is a corresponding view from below. Fig. 11 is a side elevation of the same. Fig. 12 is a vertical section taken on the line 12—12 in

Fig. 9, and partly in elevation. Fig. 13 is 55 a plan view showing the under face of the operating arm. Fig. 14 is a side view of the link or turnbuckle. Fig. 15 is a vertical section, partly in elevation, showing the support for the pawl, on a larger scale. Fig. 60 16 is a similar view showing the manner of attaching the receptacle for checking liquid.

Similar letters of reference indicate the same parts in all the figures.

A is the upper part of a door, and B the 65 lintel, and B¹ a hinge.

C is a plate of circular form having a depending flange or bracket C¹ adapted to be firmly secured to the door by screws C², and having a smoothly finished circular recess 70 on the under face matching to the annular lip or edge L¹ of a cup or container L, serving as a receptacle for the checking liquid and inclosing the checking mechanism carried on the under face of the plate C. 75

At a short distance in rear of the center of the plate is a vertical tubular boss C³ extending above the plate as shown, and receiving a shaft D carrying a crank D² at its lower end and an operating arm D¹ 80 at its upper end, extending parallel with and in the same direction as the crank. A boss C⁴ forming a continuation of the tubular boss C³, on the under face of the plate C is connected by the strengthening webs C⁵ C⁵ 85 to lugs C⁸ C⁸ cast with the plate and serving to support the checking cylinder E mounted with its axial line at a right angle to the door and held by screws E² extending through the wings E¹ on the cylinder into 90 the lugs C⁸ C⁸. On the upper face of the cylinder is a rib or thick fin E³ abutting against a boss C⁷ serving as an abutment for the cylinder in resisting the outward thrust to which it is subjected in the closing 95 movement of the door.

The piston F within the cylinder, is connected to the crank D² by a pitman F¹ and is provided with the usual valved passage f through which the checking liquid in 100 the cup L flows freely into the space behind the piston in the opening movement of the door, and when thus imprisoned escapes slowly through the small opening e and passage e¹ in the closed outer end of the cylinder 105 during the closing movement, the flow being adjusted or controlled by a screw-valve M extending from the upper face of

the plate C through a stuffingbox formed in the abutment or boss C⁷ above described.

The arm D¹ is shaped to match to the upper end of the shaft D in one position only, that is, parallel with and extending in the same direction as the crank D², and parallel with the axial line of the piston F and cylinder C when the arm stands at a right angle to the door or face of the bracket C¹, so that a movement of the arm in swinging in either direction from such central position produces the same movement of the piston relatively to its cylinder, thus permitting service with both right and left-hand doors without change of these parts.

At the outer end of the arm is a vertical pin D³ firmly mounted therein and having an upper portion D⁴ serving as a pivot for the shackle G³ in which the outer end of the screw-threaded rod G⁵ is pivoted, with the inner end screwed into a socket G which with the rod forms a link or turnbuckle. The socket is offset at the inner end as at G⁴, see Fig. 14, and carries a pivotally connected housing or bracket G¹ adapted to be secured by screws G⁷ to the casing or lintel B above the door. This offset, with the shackle G³, permits the attachment to be made at a high or low level on the lintel as conditions of installation may require.

H is a sleeve loosely inclosing the boss C³, having a vertical stud H² and oppositely inclined ratchet teeth H¹ at each side of the stud. To the latter is attached one end of a chain J³ extending axially of the spring casing or tube J which is joined at the outer end to the arm D¹. The other end of the chain is attached to a plunger or follower J¹ inclosed in the tube, serving as a movable abutment for a strong helical spring J⁵ encircling the chain and abutting at the opposite end against the inwardly curled edge of the open end of the tube J and forming a flange J⁴.

The sleeve H is held against rotation by a two-armed pawl H⁴ pivotally mounted on the center line of the plate C, engaged with one of the teeth H¹. When thus held the swing of the arm D¹ in the act of opening the door winds a portion of the chain about the boss C³ and compresses the spring J⁵ which by its reexpansion effects the closing movement. A plurality of teeth H¹ permits the force exerted by the spring to be varied, and the two series of teeth permit the sleeve to be engaged by either arm of the pawl as required for either right or left-hand doors without removing any of the parts.

At the outer end, the tube J is closed by a plug or head J² having an extension which is screwed on the screwthreaded lower end D⁵ of the pin D³. This mode of attachment permits the required slight pivotal movement of the tube on the pin in operation and

also allows the tube to be swung beneath the arm in arranging for service with right or left-hand doors, and offers the additional important advantage of easy removal by simply unscrewing the tube and its contents when by reason of a broken spring or other accident it becomes necessary to substitute a new tube, spring, and chain, which parts are furnished as a whole ready to be screwed upon the pin D³.

The inner end of the arm D¹ is enlarged and widened to form a plate or disk D⁶ perforated to match to and receive the upper end of the shaft D to which it is secured by a nut D⁷. Slots d d concentric to the shaft are provided in the disk, adapted to receive a screw K⁴ by which a hold-back or latch device is attached to the under face of the disk. The hold-back consists of a hollow casing K containing a spring K¹ exerting a thrust on a latch-bolt K² having its engaging end projecting toward the shaft and beveled in both directions laterally. From the casing K extends a flat bifurcated arm K³ having holes drilled and tapped to receive the screw K⁴ and equipped with a series of segmentally arranged ridges or teeth adapted to engage corresponding serrations provided in two series, one on each margin of the under face of the disk, and thus permit the radial position of the latch to be varied. The bifurcation of the arm K³ embraces a boss B⁹ on the under face of the disk and aids in locating and maintaining the latch in the desired position. The beveled nose of the bolt is arranged to ride over and engage a vertical post R mounted on the plate C, and thus hold the door open against the force of the spring J⁵ tending to close it. The door is released by forcibly swinging it sufficiently to disengage the nose of the bolt from the post, the door will then continue its closing movement under the force of the spring J⁵.

The curved slots d d in the disk and screw holes k k in the arm permit a wide range of adjustment as to the angle at which the door may be held in the open or partially open position.

The post R has a slotted base or foot R¹ constructed to match upon either of the long bosses C⁹ C⁹ provided upon the upper face of the plate C and be firmly engaged therewith by the screw R². In changing from a right to a left-hand door the post R is removed from one boss C⁹ to the other, and the latch-casing K correspondingly shifted to the opposite side of the disk.

To afford a strong support for the pawl H⁴ in resisting the strains to which it is subjected, it is mounted on a cylindrical boss C⁶ formed on the plate C, matching to a corresponding circular opening in the pawl, and the latter is held thereon by a screw H⁵ passing through the boss and

plate, with its conical head overlapping the adjacent face of the pawl. The conical seat thus provided receives a packing ring H^6 compressed therein by the screw to insure 5 against leakage of checking fluid, and the opening through the boss to the interior of the cup L is utilized as a filling orifice for such liquid, with the screw H^6 serving as a closure. The holding screws N by which the 10 cup is secured to the under face of the plate are provided with similar packing rings or gaskets N^1 to prevent leakage.

S is a washer applied upon the boss C^3 , held in position by the disk-portion D^6 of 15 the arm D^1 , serving as a removable annular flange above the stud H^2 to prevent vertical movement of the latter and its sleeve H , while permitting the sleeve to be applied and removed, and to rotate on the boss in 20 changing its position or adjusting the tension of the closing spring.

By extending the arm and crank in the same direction and parallel with each other, and mounting the cylinder at a right angle 25 to the door, easy installation is attained, aided by the arrangement of sleeve and pawl and by the construction and arrangement of the spring-tube and turnbuckle, and their attaching means.

30 The device as shown in Figs. 1 and 2 is arranged for easy closing conditions, with the turnbuckle or link at a right angle to the door and the operating arm at a slight inclination to the door when the latter is in 35 the closed position. In applying the device for hard closing conditions, as in overcoming the resistance offered by drafts, or by a stiff latch, the device is set with the arm at a right angle to the door and the turn- 40 buckle slightly inclined.

We claim:

1. In a door-closer, a plate adapted to be attached to a door, a shaft mounted vertically in said plate, an arm on the upper end 45 of said shaft, a screw-threaded pin in the outer end of said arm, a link pivotally secured to said arm and adapted to be attached to the door-casing, a stud held on said plate, a tube detachably and pivotally secured to said arm by being screwed upon 50 said pin and adapted to swing thereon beneath said arm, a follower in said tube, flexible connections from said follower to said stud, and a spring in said tube arranged to be compressed by said follower.

2. In a door-closer and check, a plate adapted to be attached to a door, a shaft mounted vertically in said plate, an arm on the upper end of said shaft, a screw-threaded pin in the outer end of said arm, a link 60 pivotally secured to said arm and adapted to be attached to the door-casing, a stud held on said plate, a tube detachably and pivotally secured to said arm by being screwed upon said pin and adapted to swing

thereon beneath said arm, a follower in said tube, flexible connections from said follower to said stud, a spring in said tube arranged to be compressed by said follower, a crank on the lower end of said shaft, a checking cylinder and piston, a pitman connecting 70 said crank and piston, and a receptacle for checking liquid inclosing said crank and cylinder.

3. In a door-closer, a plate adapted to be 75 attached to a door and having a vertical boss thereon, a shaft mounted in said boss, an arm on the upper end of said shaft, a sleeve rotatable on said boss and having teeth thereon, a stud on said sleeve, means 80 on said boss for holding said sleeve against vertical movement, a pawl on said plate adapted to engage said teeth, a pin in the outer end of said arm, a link pivotally secured to said arm and adapted to be attached to a door-casing, a tube secured to said pin and adapted to swing thereon beneath said arm, a follower in said tube, flexible connections from said follower to 85 said stud, and a spring in said tube arranged to be compressed by said follower.

4. In a door-closer, a plate adapted to be attached to a door, a shaft mounted therein, an arm on said shaft and connections therefrom to the door-casing, a sleeve inclosing 90 said shaft and having teeth thereon, a pawl arranged to engage said teeth, a closing spring and connections therefrom to said sleeve and a washer on said shaft above said sleeve arranged to hold said sleeve against 95 vertical movement.

5. In a door-closer, a plate adapted to be attached to a door, a shaft mounted therein, an arm on said shaft and connections therefrom to the door-casing, a sleeve inclosing 100 said shaft and having teeth thereon, a pawl arranged to engage said teeth, a closing spring and connections therefrom to said sleeve, a cylindrical boss on said plate arranged to serve as a pivot for said pawl, 105 and having an opening therein through said plate, a screw received in such opening and serving as a retaining means for said pawl, and a receptacle for checking liquid secured to said plate beneath the latter, said opening arranged to serve as a filling orifice for 110 said receptacle.

6. In a door-closer, a plate adapted to be attached to a door, a shaft in said plate, an arm on said shaft, a post, and a yielding 115 latch movable with said arm and arranged to engage said post and hold said door in an open position, and bifurcated means on the latch-carrier constructed to locate and maintain the latch in desired position.

7. In a door-closer, a plate adapted to be attached to a door, a shaft in said plate, an arm on said shaft, a post mounted on said plate, a yielding latch carried by said arm 120 and arranged to engage said post and hold 125

the door in an open position, means for varying the position of said latch upon said arm and relatively to said post.

8. In a door-closer, a plate adapted to be attached to a door, a shaft in said plate, an arm on said shaft having slots adjacent to said shaft, a casing carried by said arm and held by a screw extending through such slot, a spring-actuated bolt in said casing, and a post mounted on said plate in the path of said bolt and adapted to be engaged thereby.

9. In a door-closer, a plate adapted to be attached to a door, a shaft in said plate, an arm on said shaft having a slot on each side of the latter, serrations on said arm adjacent to said slots, a casing carried by said arm and constructed to match to said serrations, a screw passing through one of said slots and holding said casing in engagement with said arm, a boss on said plate on each side of said shaft, a post, a foot thereon having an opening matching to either of said bosses, and a spring-bolt carried by said casing and arranged to engage said post.

25. 10. In a door-closer, a plate adapted to be attached to a door, a shaft mounted therein,

an arm on said shaft, a pin in said arm, a rod pivotally connected at one end to said pin, a socket receiving said rod and revolute and adjustable on the latter, an offset-arm on said socket, and a bracket in which said offset-arm is pivoted, said bracket adapted to be attached to a door-casing.

11. In a door-closer, a plate adapted to be attached to a door, a shaft mounted therein, and an arm on said shaft, a pin in said arm, a shackle pivotally mounted on said pin, a screw-threaded rod pivotally connected at one end to said shackle, a screw-threaded socket receiving said rod, an offset-arm on said socket, a bracket in which said offset-arm is pivoted, said bracket adapted to be attached to the door-casing.

In testimony that we claim the invention above set forth we affix our signatures, in presence of two witnesses.

FRANCIS J. BAYER;
ALBERT J. ROSENTRETER.
